(57) **CLAIM**

The ornamental design for a plastic bag dispenser, as shown
and described.

DESCRIPTION

FIG. 1 is a perspective view of a plastic bag dispenser in an
open position showing my new design;

FIG. 2 is a perspective view of the plastic bag dispenser
shown in FIG. 1 but in a closed position;

FIG. 3 is a front elevation;

FIG. 4 is a top plan view;

FIG. 5 is a bottom plan view;

FIG. 6 is a plan view from the right side in FIG. 3;

FIG. 7 is a plan view from the left side of FIG. 3;

FIG. 8 is a cross-sectional view taken on line 8—8 in FIG.
3;

FIG. 9 is a cross-sectional view similar to FIG. 8 but in an
opened condition of the plastic bag dispenser; and,

FIG. 10 is a back elevation.
